UNITED STATES PATENT OFFICE.

HARRY LOEVEN, OF DOUGLAS, ARIZONA.

AMALGAMATOR.

1,418,006.

Specification of Letters Patent. Patented May 30, 1922.

Application filed August 4, 1920. Serial No. 401,096.

To all whom it may concern:

Be it known that I, HARRY LOEVEN, a citizen of the United States, and a resident of Douglas, in the county of Cochise and State 5 of Arizona, have invented certain new and useful Improvements in Amalgamators, of which the following is a specification.

My invention relates generally to amalgamators which are particularly adapted for 10 the recovery of gold from ore pulp although it is to be understood that I am not necessarily restricted to this particular adaptation.

The purpose of my invention is the provision of an amalgamator in which the ore pulp is treated within a rotated vessel which is disposed on an incline and is provided with a series of compartments through which the pulp is successively fed to effect a complete 15 recovery of the gold.

I will describe one form of amalgamator embodying my invention and will then point out the novel features in claims.

In the accompanying drawings: 20 Figure 1 is a view showing in front elevation one form of amalgamator embodying my invention, and one form of supporting and driving means therefor;

Figure 2 is a view showing in side elevation of the amalgamator and driving means shown in Figure 1;

Figure 3 is a detail perspective view of the amalgamator shown in the preceding views;

Figure 4 is a central longitudinal sectional view of Figure 3; and

Figures 5 and 6 are transverse sectional views taken on the lines 5—5 and 6—6, respectively, of Figure 4.

Similar reference characters refer to similar parts in each of the several views.

Referring specifically to the drawings, and particularly to Figures 1 and 2, 15 designates a base to which is fixed supporting standards 16 and 16^a in which is journaled the opposite ends of a shaft 17. As shown in Figure 1, the standards 16 and 16^a are of different lengths and the right-hand end of the shaft 17 is journaled at a point above 20 the opposite end of the shaft so that the shaft assumes an inclined position. The lower end of the shaft 17 projects beyond the outer side of the standard 16 and has fixed thereto a frusto-conical pulley 18.

To drive the shaft 17 at a slow rate of speed in one direction, I provide a mecha-

nism which in the present instance comprises a shaft 19 journaled in standards 20 and disposed above the shaft 17, as clearly shown. The lower end of the shaft 19 is 60 provided with a pulley 21 which is fixed to the shaft and a second pulley 22 which is loosely mounted on the shaft and constitutes an idler. The shaft 19 also carries a driving pulley 23 to which any suitable power may 65 be applied for rotating the same, as will be understood. The shaft 19 is operatively connected to the shaft 17 by means of an endless belt 24 which is trained about the pulleys 18 and 21. When it is desired to disconnect the driving shaft 19 from the shaft 17, the belt 24 is shifted to the pulley 22, and the latter being loosely mounted on the shaft 19 the driving of the shaft 17 is discontinued.

The amalgamator which forms the subject-matter of my invention is generally designated at A in Figures 1 and 2 and is shown as mounted upon the shaft 17. As shown in Figures 3 to 6 inclusive, the amalgamator A 80 comprises a vessel of substantially rectangular formation which is formed of suitable material and comprises side plates 25 connected to other side plates 25^a. The ends of the vessel are partly closed by end plates 26 85 and 26^a which are secured to the plates 25 and 25^a and are formed with relatively large openings 27 and 27^a, respectively. As illustrated to advantage in Figure 3, the shaft 17 extends axially through the vessel and the latter is secured to the same for rotation therewith by means of intersecting cross bars 28 which are secured within the vessel and are disposed within suitable recesses formed in the shaft. The cross bars 28 are 90 secured within the recessed portions of the shaft 17 by means of bolts 29 so that a rigid connection is formed between the vessel and the shaft to cause the former to rotate with the latter. It will be noted that the cross 95 bars 28 are disposed adjacent the opposite ends of the vessel so that ready access may be had to the bolts 29 to connect or disconnect the vessel from the shaft.

To effect a complete recovery of the gold 105 or other precious ore from ore pulp the amalgamator is provided interiorly of the vessel with a plurality of riffles or partitions 30 and 30^a. As shown in Figures 4, 5 and 6, the riffles 30 are arranged in pairs, with 110 the riffles of each pair spaced apart and connecting the plates 25 of the vessel. The rif-

fies 30^a are arranged in a similar manner but at right angles to the riffles 30 so that they connect the plates 25^a. Each adjacent pair of riffles 30 and 30^a are secured to each other and to the walls of the vessel, and coact with each other to provide rectangular openings 31. As shown in Figure 4, adjacent pairs of riffles 30 and 30^a are arranged at regular spaced intervals throughout the 10 length of the vessel thus providing a plurality of compartments K any two of which are in communication through the openings 31.

In the operation of the amalgamator, the 15 several compartments K are partially filled with quicksilver, whereupon the belt 24 which is normally trained about the idle pulley 22 is shifted to the pulley 21 so that the shaft 17 is caused to slowly rotate. By virtue of the riffles 30 and 30^a the quicksilver in 20 any one of the compartments is maintained therein during rotation of the vessel, it being understood that the quantity of the quicksilver in each compartment is sufficient to 25 perform the recovering operation without spilling and passing to the next compartment. The ore pulp is introduced into the vessel at its upper end through the opening 27, a suitable trough T being provided for 30 this purpose. With the amalgamator slowly rotating the ore pulp is successively fed through the several compartments and finally exits through the opening 27^a. During 35 the passage of the ore pulp, the quicksilver is thrown from one side of the vessel to the other thereby causing the same to collect the particles of gold, the tailings being left to pass through the several openings 31 and outwardly out of the opening 27^a. Because 40 of the several compartments K and the recovering material contained therein, it is obvious that the ore pulp is successively subjected to a plurality of recovering processes so that during the passage of the same 45 through the amalgamator a complete recovery of the gold is effected.

As shown in Figure 5, one of the walls 25^a is formed with a longitudinally extending slot S which is cut in the wall at a tangent 50 of a circle with the axis of the shaft 17 as a center. Since the amalgamator rotates in the direction of the arrow in Figure 5, the material contained within the vessel will

not be discharged through the slot S because the transverse inclination of the latter is 55 such that the material, although entering the slot when the corresponding side plate 25^a is inverted, will be immediately returned to the vessel when such plate moves to a vertical position. When, however, it is desired to 60 extract the gold and quicksilver from the vessel the rotation of the latter is discontinued and then turned slowly in the opposite direction by hand. This causes the gold and quicksilver to be discharged through 65 the slot S as the inclination of the latter is now such that the material entering the slot when the corresponding side plate is inverted, gravitates from the slot and exteriorly of the vessel when the side plate moves 70 to a vertical position.

Although I have herein shown and described only one form of amalgamator embodying my invention, it is to be understood that various changes and modifications may 75 be made herein without departing from the spirit of the invention and the spirit and scope of the appended claims.

Having thus described my invention, I 80 claim:

1. An amalgamator comprising a vessel, a plurality of partitions arranged in spaced relation within the vessel and each consisting of pairs of overlapping sections, the sections of each pair being arranged in spaced 85 relation whereby to define a plurality of openings, an operating shaft extending through said vessel, and means rigidly connecting the shaft to said vessel, said vessel being provided with a longitudinal slot, the walls of which are inclined with respect to the surface of the vessel.

2. An amalgamator comprising a vessel, a plurality of partitions arranged in spaced relation within the vessel and having aligned 95 openings through which the material passes, a shaft extending centrally through said openings and constituting a means to rotate said vessel, and means to rigidly connect said shaft to said vessel, said vessel being provided in one side with a longitudinal slot, the walls of which are inclined with respect to the surface of the wall in which the slot is located.

HARRY LOEVEN.
